UNITED STATES PATENT OFFICE.

GEORGE H. KING, OF SALT LAKE CITY, UTAH.

WASHBASIN.

1,120,823.

Specification of Letters Patent. Patented Dec. 15, 1914.

Application filed February 14, 1914. Serial No. 818,772.

To all whom it may concern:

Be it known that I, GEORGE H. KING, a citizen of the United States, residing at Salt Lake City, in the county of Salt Lake and 5 State of Utah, have invented certain new and useful Improvements in Washbasins, of which the following is a specification, reference being had to the accompanying drawings.

10 This invention relates to new and useful improvements in wash basins, particularly of the tiltable type.

The object of the present invention resides in the provision of a wash basin which 15 presents a smooth concave surface throughout and which is so mounted that it may be emptied by tilting it so that the necessity of using the usual plug and outlet, with its consequent inconveniences, is done away 20 with.

A further object of the invention resides in the provision of such a tiltable wash bowl which may be associated with any conventional form of fixed wash basin with but 25 little modification thereof.

A still further object of the invention resides in the provision of such a device which may be easily operated and which comprises a minimum number of parts so that it may 30 be readily cleansed and will prove durable in use and possess the further advantage of being capable of manufacture at a low cost.

With these and other objects in view, the invention resides more particularly in the 35 novel combination, formation and arrangement of parts more fully hereinafter described and particularly pointed out in the appended claim.

Reference is to be had to the accompanying 40 drawing wherein similar characters of reference designate corresponding parts throughout the several views, in which—

Figure 1 is a top plan view of the tiltable basin shown in conjunction with a conventional form of fixed basin. Fig. 2 is a vertical sectional view taken on the line 2—2 of Fig. 1.

50 Referring more particularly to the accompanying drawings, there is shown a conventional form of fixed basin comprising the usual bowl 5 provided in its bottom with the outlet 6 and having the plate 7 surrounding its top edge.

The tilting basin 8 comprises a single 55 piece of metal or other suitable material

bent in proper form and having its edge portion bent backwardly at 9. For supporting and actuating this basin, the bowl 5 is provided at one side with a socket 9 opening at the inner face of the bowl and at the top 60 of the bowl. The bowl is provided at a point diametrically opposed to the socket with a bore 10 which has its bottom in alignment with the bottom of the socket. A band 11, surrounds and is secured to the upper 65 portion of the tiltable basin and extending from this band is a trunnion 12 which is journalled seated in the socket 9. Extending from the band at a point in alignment with the axis of the pintle is a shaft section 13 70 which extends through the bore 10 outwardly of the plate 7. Fixed to the outer end of this shaft section is an actuating arm 14 which is grasped and rocked to tilt the basin. In operation the basin 8 is filled with 75 water. When it is desired to empty the basin, the arm 14 is rocked and the basin swings on its pivot and discharges its contents into the bowl 5 from whence they pass through the outlet 6.

By this construction the usual unsanitary feature of the outlet stopper is done away with. A device has thus been provided which is efficient in use, and which may be adapted to any form of fixed wash basin 85 with but slight modification thereof. It is also to be noted that by the use of my device, the necessity of having a supplementary channel in the basin for the discharge of the water is done away with, because by the construction and arrangement of the parts, I have invented, the basin cannot overflow owing to the fact that as the outlet in the bowl 5 is always left open should the tilting basin 8 be filled, any further supply of 90 water, or overflow, will merely pass down into the main bowl 5 and out through the discharge outlet 6.

What I claim is:

The combination with a fixed bowl having 100 an open socket in the wall thereof at its upper edge, said bowl having an opening extending therethrough adjacent its upper edge at a point diametrically opposite to the socket, a supporting band having trunnions 105 extending from diametrically opposite points thereof, said trunnions being of relatively different lengths, the shorter of said trunnions resting loosely in the socket, the longer of said trunnions being journalled dis- 110

posed in the opening in the bowl and extending through and beyond the same, an actuating arm detachably connected to the extremity of the longer trunnion, a basin disposed within the bowl, and said basin having a flange by means of which the same is connected to the band.

In testimony whereof I hereunto affix my signature in the presence of two witnesses.

GEORGE H. KING.
